UNITED STATES PATENT OFFICE.

LESLIE S. HACKNEY, OF ST. PAUL, MINNESOTA.

VENTILATING DEVICE.

No. 877,420.

Specification of Letters Patent.

Patented Jan. 21, 1908.

Application filed August 9, 1907. Serial No. 387,772.

To all whom it may concern:

Be it known that I, LESLIE S. HACKNEY, of St. Paul, Ramsey county, Minnesota, have invented certain new and useful Improvements in Ventilating Devices, of which the following is a specification.

My invention relates to a ventilating apparatus and the object of the invention is to provide means capable of quick and easy attachment to a window for the purpose of supplying fresh air to the room and removing the foul air therefrom.

A further object is to provide an apparatus, that is particularly adapted for sick rooms and movable from one room to another when used in a hospital to supply fresh air to the patient and remove the impure air around the bed.

The invention consists generally in various constructions and combinations, all as hereinafter described and particularly pointed out in the claims.

In the accompanying drawings, forming part of this specification, Figure 1 is a perspective view showing the application of my invention to a window, and the manner of conducting the fresh air to the bed and removing the impure air therefrom. Fig. 2 is a detail view illustrating the adjustable feature of the board on which the apparatus is mounted, to adapt it for windows of different width. Fig. 3 is a detail view illustrating the outside of the board. Fig. 4 is a sectional view illustrating the intake and outlet pipes permanently inserted in the outer wall of the building. Fig. 5 is a detail sectional view illustrating the position of the intake pipes and a cap for closing the same.

In the drawing, 2 represents the wall of the room, 3 the window sash, 4 a shelf adapted to rest on the sill 5, and 6 a plate adapted to fit between the sill and the sash and having a movable extension 7 at one end adjustably connected with the part 6 through a slot 8 and thumb screw 9 to allow the board to be fitted into windows of different widths. 10 is a suction fan having a pipe 11 extending through the board 6 and upwardly therefrom to a point near the bottom of the upper sash 50 and having an open outer end through which the impure air drawn from the room by the operation of the fan is discharged.

A tube 12 is connected to the fan 10 and has a funnel 13 at its opposite end which, as shown in Fig. 1, depends to a point near the floor, a sufficient suction being created by the

revolution of the fan to withdraw all the foul or impure air which collects in the lower part of the room. The tube 12 may be made of any suitable length to permit the funnel to be placed in any part of the room or under or in the bed if desired.

I prefer to provide a fresh air tube 14 having a funnel 15 at its inner end and fitting within an opening 16 in the extension 7, over which a gauze screen 17 is placed. This tube 14 may be hung over the head of the bed where the fresh air can be delivered to the patient and whenever desired the tube and funnel can be moved to other points in or on the bed or to other parts of the room. The funnel may be held in the hand and the fresh air inhaled.

It is extremely difficult to ventilate a sick room, particularly where the building has not been constructed with a ventilating apparatus and it is extremely dangerous to open a window where the draft will blow directly upon the sick person. It has also been found very difficult to properly ventilate bed clothing without danger of exposing the patient to cold or drafts. With this apparatus it will be unnecessary to move the person in the bed, the fresh air tube being placed in any desired position in the room or on the bed and the impure air funnel being adjusted wherever it is desired to create the circulation and change the air. In hot weather this apparatus will be found very useful as the circulation can be maintained through the bed and the impure air entirely removed from the room.

I prefer to employ an electric motor 18 for driving the fan, also mounted on the board 6 and capable of movement therewith from place to place and adapted to be driven by the electric light current which may be delivered thereto through the conductor 19 that is plugged into the light 20 in the usual way.

Instead of having the intake and exhaust tubes mounted in a board that is capable of adjustment in a window, these tubes may be connected with fresh air and foul air pipes permanently arranged in the building wall. The operation of the apparatus, however, would be substantially the same. The use of the board renders the device capable of more general application as it permits the ventilation of old buildings where no pipes are provided in the wall and could not be conveniently installed.

In Figs. 4 and 5 I have shown the ventilating tubes used in connection with intakes and outlet pipes that are permanently arranged in the wall of the building. 21 represents the intake pipe arranged in the building wall above the window and having an inner end on which the tube 14 is adapted to be fitted. A removable cap 22 is provided for closing the inner end of the pipe when 10 the device is not in use.

For taking out the foul air I prefer to provide a flue 23 mounted on the outside of the wall of the building and extending up to a point near the roof. The lower end of the 15 pipe 23 is extended inwardly through the base board and the foul air tube may be fitted over this inner end, or in some instances the tube may be omitted and the foul air allowed to pass directly into the open end of the flue. 20 Considerable suction will be created in the flue 23 and the foul air accumulating in the lower part of the room will pass off therethrough.

I have shown this ventilating device in 25 connection with a bedroom but do not wish to confine myself to such use as it is well adapted for ventilating purposes in living and other rooms of residences, hotels, or other buildings and in the compartments or state- 30 rooms of cars and steamships.

I claim as my invention:

1. A ventilating apparatus comprising a board adapted to be fitted into a window between the lower sash and sill, a suction fan 35 having a pipe extending through said board to the open air, said fan being attached to said board and movable therewith from place to place, an electric motor also attached to said board and connected with said 40 fan, a flexible tube connected with said fan and having a funnel at its free end adapted to be inserted in or under a bed, and a second flexible tube extending through said board to the open air and having a discharge funnel 45 at its free end, substantially as described.

2. The combination, with a board, having an adjustable extension to adapt it for windows of different width, and capable of fitting 50 between the lower sash of the window and the sill, a suction fan having a pipe extending

through said board to the open air, a flexible tube connected with said suction fan, a funnel attached to the free end of said tube, an electric motor connected with said fan for operating the same and also attached to said 55 board and movable therewith from place to place, and a fresh air tube connected with an opening in said board and having a funnel at its free end and through which fresh air is delivered into the room, substantially as de- 60 scribed.

3. The combination, with a board composed of adjustable sections and adapted to be fitted to windows of different width between the lower sash and the sill, an impure 65 air pipe extending through said board and upwardly to a point near the top of the sash, a flexible tube connected with said pipe, and a second flexible tube extending into an opening in said board and communicating therethrough with the outside air, substantially as 70 described.

4. A ventilating apparatus comprising pipes arranged to extend through an outer 75 wall and having open outer ends communicating with the atmosphere and tubes adapted to be fitted on the inner ends of said pipes and having funnels, one of said tubes serving as a fresh air inlet and the other tube as an exhaust for the foul air, substantially as de- 80 scribed.

5. A ventilating apparatus comprising pipes arranged to extend through an outer wall and having open outer ends communicating with the atmosphere and tubes adapted to be connected to the inner ends of said 85 pipes, one of said tubes serving as a fresh air inlet and the other tube as an exhaust for the foul air, both of said tubes having their inner 90 ends exposed to the atmosphere and capable of being moved from place to place, whereby the ventilation of the space may be regulated, substantially as described.

In witness whereof, I have hereunto set my hand this 29th day of July, 1907.

LESLIE S. HACKNEY.
